UNITED STATES PATENT OFFICE.

CHRISTOPHER H. SMITH, OF PHILADELPHIA, PENNSYLVANIA, ASSIGNOR
OF ONE-HALF HIS RIGHT TO BENJ. B. MILES, OF SAME PLACE.

IMPROVEMENT IN BUREAU-BEDSTEADS.

Specification forming part of Letters Patent No. **186,632**, dated January 23, 1877; application filed
May 26, 1874.

To all whom it may concern:

Be it known that I, CHRISTOPHER H. SMITH, of the city of Philadelphia and State of Pennsylvania, have invented a new and useful Bureau-Bedstead, of which the following is a specification:

The invention consists of a folding bedstead, which, when folded, is identical in appearance to a bureau, such as is usually employed for keeping papers or clothing, as is hereinafter shown and described.

Figure 1 is a perspective view, showing the bedstead closed up. Fig. 2 is a perspective view of the bedstead open and ready for use.

A is a bedstead, which, when folded, as shown at Fig. 1, presents the appearance of a bureau or case, such as is used for containing clothing. The front B of the bedstead is divided from the body C at the line *a*, and hinged to it, which forms, when open, the horizontal part D of the bed, Fig. 2. The top E is divided at the line *b*; the part F forms the foot-board G, Fig. 2, of the bed. To support the foot or end of the bed, when open, feet *c* are provided, which, when not in

use, fold into the front of the bureau. The interior of the bureau or case, when closed, is occupied by the mattress H, pillow I, and the bed-clothing. Supporting-hooks *d* at each side keep the front closed against the body. A drawer, J, which extends across the bottom of the case is for containing the necessary bed-clothing.

I am aware that the stationary part A and the two-part top E are not new, and I therefore disclaim them.

I claim as my invention—

The stationary hollow body C, with top E, in combination with the folding front B, with the part F, forming both a foot-board of the bedstead and the continuation of the top E of the bureau, all connected, arranged, and operating as set forth.

In testimony whereof I hereunto sign my name in presence of two subscribing witnesses.

CHRISTOPHER H. SMITH.
